UNITED STATES PATENT OFFICE.

CHARLES S. SHALLENBERGER, OF ST. LOUIS, MISSOURI, ASSIGNOR TO SCULLIN-GALLAGHER IRON AND STEEL COMPANY, OF ST. LOUIS, MISSOURI, A CORPORATION OF MISSOURI.

DRAFT-RIGGING FOR RAILWAY-CARS.

976,508.

Specification of Letters Patent. Patented Nov. 22, 1910.

Application filed October 29, 1908. Serial No. 460,101.

To all whom it may concern:

Be it known that I, CHARLES S. SHALLENBERGER, a citizen of the United States, residing at St. Louis, Missouri, have invented a certain new and useful Improvement in Draft-Riggings for Railway-Cars, of which the following is a full, clear, and exact description, such as will enable others skilled in the art to which it appertains to make and use the same, reference being had to the accompanying drawings, forming part of this specification.

This invention relates to draft riggings, and particularly to the drawbar yokes used in tandem draft riggings.

One object of my invention is to provide a yoke that is composed of a number of independent sections which are detachably connected together so that a new section can be substituted for a broken section and thus overcome the necessity of discarding the entire yoke in case any portion thereof breaks. And another object of my invention is to provide a cast metal yoke for tandem draft riggings which is stronger than the yokes that have heretofore been in use.

Briefly described, my invention consists in a yoke composed of a number of separate sections or members arranged in longitudinal alinement with each other and detachably connected together.

In the preferred form of my invention, as herein shown, the sections of the yoke are approximately U-shaped, and each section has a portion that interlocks with an adjacent section so as to enable the sections to be taken apart and assembled easily. The first section of the yoke is connected to the drawbar and the other section or sections are arranged one behind the other in longitudinal alinement with the first section, the cross webs of said sections coöoperating with the followers of the draft rigging and the legs of said sections embracing said followers and the shock-absorbing elements of the rigging.

A yoke of the construction above described greatly reduces the cost of maintaining draft riggings owing to the fact that the entire yoke does not have to be discarded in case any portion thereof breaks.

Figure 1 of the drawings is a side elevational view of a draft rigging constructed in accordance with my invention; Fig. 2 is a

of said draft rigging; Fig. 3 is a perspective view of the yoke; and Fig. 4 is a perspective view of a yoke of slightly different construction from the one shown in Fig. 3.

Referring to the drawings which illustrate a draft rigging that comprises two sets of springs or shock-absorbing elements, 1 designates the springs or shock-absorbing elements, each of which is arranged between a front follower 2 and a rear follower 3 which coöperate with lugs or stops on cheek plates 4, as shown clearly in Fig. 2.

My improved yoke is composed of a plurality of separate sections or members which are substantially U-shaped and arranged in longitudinal alinement with each other, the front section A being connected to the drawbar 5 by fastening devices 6, and the rear section B being detachably connected to the front section A. The front section A is preferably provided with lips 7 which interlock with lugs on the drawbar so as to reduce the shearing strains on the fastening devices 6, and the rear section B is provided with lugs or extensions 9 that project into slots or pockets 8 in the rear end of the section A. A fastening device 10 is preferably passed through the rear section B and the portion of section A which said rear section embraces so as to hold said sections in longitudinal alinement with each other and also reduce the shearing strains on the lugs 9. The cross web of the front section A is arranged between the rear follower 3 of the front spring and the front follower 2 of the rear spring, and the cross web of the rear section B coöperates with the rear follower 3 of the rear spring. The extensions 9 on the rear section B of the yoke, which project into the notches 8 in the front section A, receive some of the shocks and strains to which the cross web of the section A is subjected and thus reduce the liability of said cross web being sheared off or broken and the fastening device 10 that passes through the sections reduces the shearing strains on the extensions 9.

In case one section of the yoke breaks it is not necessary to discard the entire yoke for a new section can be substituted easily for the broken section and thus repair the yoke at approximately one-half the cost of a one-piece metal yoke of the kind heretofore in use.

If desired, the cross webs of the sections

A and B can be provided with curved faces 11 as shown in Fig. 2 so as to permit the draw-bar to swing or rock while the car is going around curves.

5 In Fig. 4 I have illustrated a slightly modified form of my invention wherein the rear section B' of the yoke is provided with lips or projections 9^a having concaved inner edges which conform to the concaved bottom 10 walls of the slots 8^a into which said lips project, the legs of said rear section B' also being provided with concaved faces 12 that engage convexed surfaces on the front section A, as shown clearly in Fig. 4. With such a 15 construction it is not necessary to connect the sections of the yoke together by means of fastening devices as the shocks to which the yoke is subjected when in use do not tend to make the sections rotate relatively to each 20 other. In assembling the parts of the yoke shown in Fig. 4 the lips or extensions 9^a on the rear section B' are partially inserted in the slots 8^a and one section of the yoke is then rotated relatively to the other until the

two sections are in longitudinal alinement 25 with each other.

Having thus described my invention, what I claim as new and desire to secure by Letters Patent is:

A yoke for tandem draft riggings, comprising two substantially U-shaped members arranged in longitudinal alinement with each other and with their legs projecting in the same direction, the cross web of the front member being provided with slots whose 35 bottoms are convexed, and lugs on the rear member that project into said slots, the lower ends of said lugs being concaved so that they will conform to the shape of the bottoms of said slots. 40

In testimony whereof I hereunto affix my signature in the presence of two witnesses, this twenty-fourth day of October, 1908.

CHARLES S. SHALLENBERGER.
